WELDER'S HOOD

Filed Aug. 18, 1930

UNITED STATES PATENT OFFICE

JOHN S. NORTON, OF SAN FRANCISCO, CALIFORNIA, ASSIGNOR OF ONE-THIRD TO WILLIAM F. HOLLINGSWORTH, OF SAN FRANCISCO, CALIFORNIA

WELDER'S HOOD

Application filed August 18, 1930. Serial No. 476,188.

The present invention relates to improvements in a welder's hood, and its principal object is to provide a convenient means for operating the lens of the hood so that the welder, when desiring to view the work may raise the lens without the use of his hands and without changing his position.

More particularly it is proposed in the present invention to use a pressure means for operating the lens and to arrange the pressure means in such a manner that the same may be actuated by a bulb arranged to lie in the arm pit of a person wearing the hood so that the lens may be raised by squeezing the upper arm against the body.

It is further proposed in the present invention to use a hood made of leather or fabric or flexible composition and to arrange the operating means in such a manner as to allow of free access of air into the hood and to give as much comfort to the operator as is possible.

Further objects and advantages of my invention will appear as the specification proceeds.

The preferred form of my invention is illustrated in the accompanying drawings, in which

Figure 1 shows my hood on a welder; Figure 2 shows a rear view of the front section of the hood including the principal parts of my operating mechanism;

Figure 3 a vertical section taken along line 3-3 of Figure 2, and

Figure 4 a horizontal section taken along line 4-4 of Figure 2.

While I have shown only the preferred form of my invention, I wish to have it understood that various changes or modifications may be made within the scope of the claims hereto attached without departing from the spirit of the invention.

In its preferred form my hood indicated at 1 is preferably made of leather or flexible composition of suitable kind, and has a frame 2 made of metal provided in the front portion thereof. This frame for which a suitable opening is made in the hood material is fastened to the marginal portion of the latter by an inner frame 3, the margin of

the opening being confined between the two frames and the two frames being interconnected by a plurality of rivets 4 or other suitable means.

The frame itself has mounted over its opening a hinge 5 to which is pivoted the lens frame 6. The lens frame carries an inner lens 7 of eye protecting properties, held in place by means of springs 8 and an outer lens 9 of ordinary glass held in place by two guide members 10 and bottom members 11.

One of the edges of the lens has an arm 12 extending rearwardly therefrom, and the outer end of this arm is connected by means of a link 13 to a piston rod 14 extending from a piston 15, which latter is reciprocable in a cylinder 16 mounted adjacent the lens opening. The piston rod passes through a guide plate 17, and a spring 18 surrounding the piston rod and bearing on the guide plate has a tendency to push the piston upward in the cylinder. The upper end of the cylinder has a short pipe 19 extending therefrom, and this pipe connects with a flexible tube 20, having a bulb 21 at its outer end so that by compression of the bulb air is forced into the cylinder, and urges the piston 15 outward, whereby through the action of the link 13 and the arm 12, the lens is thrown upward into the dotted line position shown in Figure 3. The tube 20 is preferably made sufficiently long that it can be guided around the back of a person as shown in Figure 1, and allow the bulb 21 to be held in one of the arm pits, and to be compressed by a slight movement of the upper arm. For the convenience of the operator a spring clamp 22 may be fastened to the bulb whereby the latter may be secured to the upper arm of the individual using the device.

Above the lens, I preferably fasten a spacing member 23 consisting of a fairly wide strip of spring metal having a central portion 24 corresponding to the outline of the human forehead, and having two legs 25 by means of which it may be fastened to the top of the frame. A suitable elastic 26 fastened to the two ends of the member 24 may be guided around the head for holding the metal

portion of the hood in position relative to the forehead.

The advantages of my invention will be readily understood from the foregoing description. The hood made of flexible material may be more easily carried and accommodated in smaller space than the hood made of rigid material. It is particularly adapted for overhead work and for work in tight places. The operating means for the lens is particularly effective and easily operated. The bulb being fastened to the upper arm, does not interfere with any of the other operations of the welder, and whenever it becomes necessary for the latter to raise the lens so as to have an opportunity to inspect the work, he need only press his forearm against his body, which will cause the lens to swing upward on the hinge 5. If he swings the lens far enough the arm 12 and the link 13 become practically aligned for holding the lens in wide open position. Under normal conditions the spring 18 automatically returns the lens, and the other movable parts into proper position as soon as the pressure is relieved.

I claim:

1. A welder's hood of the character described having a movable lens, pressure operated means for actuating the same, a bulb and a flexible tube connecting the bulb and the said means, the flexible tube being sufficiently long to allow the bulb to be positioned in the arm pit of a person wearing the hood and to be compressed by a movement of the welder's arm, and means for fastening the bulb in place.
2. A welder's hood of the character described having a movable lens, pressure actuated means for actuating the lens, a bulb having a limb encircling member secured thereto adapted to embrace a limb of the welder and allowing the bulb to be compressed by a movement of the limb, and a flexible tube connecting the bulb with the pressure actuated means.

JOHN S. NORTON.
